STAPLING MACHINE

Henry Ruskin, New York, N. Y., assignor to Swingline,
Inc., Long Island City, N. Y., a corporation of New
York

Application July 9, 1957, Serial No. 46,871

Term of patent 14 years

(Cl. D74—1)

FIG. 1

FIG. 4

FIG. 5

Des. 182,772

PAGE 2

FIG. 2

FIG. 6

FIG. 3

Fig. 1 is a side perspective view of a stapling machine illustrating my new design;

Fig. 2 is an enlarged side elevational view thereof;

Fig. 3 is a top plan view;

Fig. 4 is a front elevational view;

Fig. 5 is a rear elevational view; and

Fig. 6 is a side perspective view on a reduced scale of the safety guard as it appears removed from the stapling machine.

The essential features of my design reside in the portions shown in solid lines on the drawing.

I claim:

The ornamental design for a stapling machine, as shown and described.
